DESIGN FOR A BLOCK UNIT FOR FLEXIBLE PANELS

Gregory Soussloff, New York, N. Y., assignor to Neo Plastics Products Company, New York, N. Y., a partnership

Application September 18, 1944, Serial No. 115,355

Term of patent 14 years

(Cl. D87—3)

To all whom it may concern:

Be it known that I, Gregory Soussloff, a citizen of the United States, residing at New York, in the county of New York and State of New York, have invented a new, original, and ornamental Design for Block Units for Flexible Panels, of which the following is a specification, reference being had to the accompanying drawing, forming a part thereof.

In the drawing:

Fig. 1 is an enlarged perspective view of a

block unit for flexible panels, showing my new design.

Fig. 2 is a top plan view; and

Fig. 3 is a bottom plan view of the same.

Fig. 4 is a sectional view taken on the line 4—4 of Fig. 1.

I claim:

The ornamental design for a block unit for flexible panels, as shown.

GREGORY SOUSSLOFF.
